(57) **CLAIM**

The ornamental design for a medical imaging scanner, as shown and described herein.

DESCRIPTION

FIG. 1 is a perspective view of a medical imaging scanner having a design thereon in accordance with an embodiment of the present invention.

FIG. 2 is a side elevational view of the medical imaging scanner of FIG. 1.

FIG. 3 is a front elevational view of the medical imaging scanner of FIG. 1; and,

FIG. 4 is a top plan view of the medical imaging scanner of FIG. 1.

The broken lines in the drawing views are included for the purpose of illustrating portions of the medical imaging scanner that form no part of the claimed design.

1 Claim, 4 Drawing Sheets

FIG. 1

FIG. 2

FIG. 3

FIG. 4
